F. J. WALLACE

STOCK REGULATOR FOR PAPER MACHINES

Filed June 2, 1923

INVENTOR
FRANCIS J. WALLACE.

BY Fetherstonhaugh Esq. M.A.

Patented July 7, 1925.

UNITED STATES PATENT OFFICE.

FRANCIS JOSEPH WALLACE, OF SAULT STE. MARIE, ONTARIO, CANADA.

STOCK REGULATOR FOR PAPER MACHINES.

Application filed June 2, 1923. Serial No. 643,028.

To all whom it may concern:

Be it known that I, FRANCIS JOSEPH WALLACE, a subject of the King of Great Britain, and a resident of the city of Sault Ste. Marie, in the Province of Ontario and Dominion of Canada, have invented certain new and useful Improvements in Stock Regulators for Paper Machines, of which the following is a specification.

10 This invention relates to improvements in stock regulators for paper machines, and the objects of the invention are to provide simple and efficient means whereby the flow of pulp will be automatically controlled by the 15 supplying of additional water when it becomes too thick.

Further objects are to provide means for automatically thinning the pulp in its flow when necessary and whereby the several 20 parts will efficiently and more satisfactorily perform the various functions required of them.

With the foregoing and other objects in view, the invention consists essentially in 25 the novel arrangement and construction of parts described in the present specification and illustrated by the accompanying drawings that form part of the same.

Referring to the drawing, in which like 30 characters of reference indicate corresponding parts,

The figure is an enlarged vertical section through the pulp box.

In the drawing, A is the device as a whole 35 comprising the pulp box B of any suitable form and constructed of any suitable material. This box is fed by means of an intake pipe 10 at the top, through which the pulp is delivered into the top portion of the box.

40 11 is a partition in the box extending vertically and substantially the full length thereof, leaving at the top and bottom gaps 12 and 13 whereby the overflow of the pulp supplied to the upper portion 14 of the box overflows through the passage formed by said partition and the side of the box until it reaches the bottom of the latter.

The main body of the pulp is fed from the top of the box by a conduit or pipe 15

into a suitable hopper 17 and through the 50 outlet 18 of the hopper where it mixes with the overflow referred to. The pulp in its travel must be regulated to a certain consistency so that if it is too thick in the hopper 17 it will not flow easily therethrough 55 and to counter-act this, I provide automatically operated means for injecting water into the pump.

These means comprise a float 19 adapted to be raised by the too thick pulp. This 60 float on being raised in turn through suitable connections 21 and 22 releases the valve 23 which connects with suitable pump means that supply the box at the top. 24 is the water line which runs from the valve 23 to 65 the pump and the release of the valve supplies water as required to thin down the pulp mixture.

From the foregoing, the operation of my 70 device and the satisfactory results obtained therefrom will be apparent.

As many changes could be made in the above construction and many apparently 75 widely different embodiments of my invention within the scope of the claims, constructed without departing from the spirit or scope thereof, it is intended that all matter contained in the accompanying specification and drawings shall be interpreted as 80 illustrative and not in a limiting sense.

What I claim as my invention is:

1. In a device of the character described, the combination with a pulp box formed with a pulp receiving compartment at the top and a pulp containing compartment communicating with said upper compartment whereby the overflow of the pulp is delivered to the second-named compartment, a hopper communicating with the upper compartment and designed to discharge into the lower compartment, float means in said hopper link-connected to a valve in turn connected to the supply pump whereby on the float being raised water is delivered automatically by the pump to thin the pulp and facilitate the flow thereof into the lower compartment.

2. In a device of the character described,

a pulp box provided with pulp intake means, a pulp receiving compartment and a pulp containing compartment, overflow means connecting said compartments, a receiving hopper for the containing compartment and means connecting said hopper with the pulp receiving compartment, and valve operating means in the hopper adapt-

ed to be operated on the contents of the hopper becoming too dense. ¹⁰

In witness whereof I have hereunto set my hand in the presence of two witnesses.

FRANCIS JOSEPH WALLACE.

Witnesses:

VALENTINE McNAMARA,
DORA CRAWFORD.
